UNITED STATES PATENT OFFICE.

EDMUND A. STEINMAN, OF CHICAGO, ILLINOIS.

DESIGN FOR TRIMMING FOR METAL BEDSTEADS.

45,736.

Specification for Design.

Patented May 5, 1914.

Application filed January 16, 1914. Serial No. 812,606. Term of patent 3½ years.

To all whom it may concern:

Be it known that I, EDMUND A. STEINMAN, a citizen of the United States, residing at Chicago, in the county of Cook and State of Illinois, have invented a new, original, and ornamental Design of Trimings for Metal Bedsteads, of which the following is a specification, reference being had to the accompanying drawings, forming a part thereof.

In the drawing: the figure is a side elevation of a trimming for metal bedsteads, showing my new design.

I claim—

The ornamental design for a trimming for metal bedsteads, as shown.

EDMUND A. STEINMAN.
